UNITED STATES PATENT OFFICE.

GEORGE W. OLNEY, OF MINNEAPOLIS, MINNESOTA.

PROCESS OF MANUFACTURING ONE-PIECE PACKING RINGS.

Application filed March 21, 1921. Serial No. 454,143.

To all whom it may concern:

Be it known that I, GEORGE W. OLNEY, a citizen of the United States, residing at Minneapolis, in the county of Hennepin, and ⁵⁰ State of Minnesota, have invented certain new and useful Improvements in Processes of Manufacturing One-Piece Packing Rings, of which the following is a specification.

My invention relates to process of manufacturing one piece split packing rings, and an object is to provide a ring of this character which will be gas and steam tight. Heretofore in order to prevent leak in split packing rings, it has been customary to provide a secondary or supplementary split ring which lies within the main ring, this inner ring having a special split which seals the split of the outer or main ring. A particular object, therefore, of my invention is to provide a one piece ring in which the split will be effectually sealed without the employment of the supplementary ring. In this manner the process of manufacture is very much simplified, and the operation of the ring is more effective on account of not having two parts which may get out of adjustment relatively to each other.

The full objects and advantages of my invention will appear in connection with ⁷⁵ the detailed description thereof, and the novel features embodied in my inventive idea will be particularly pointed out in the claim.

In the accompanying drawings, Fig. 1 is a view in perspective of a blank ring from which my improved split ring is manufactured. Fig. 2 is a fragmentary view of the ring after it has been step-cut. Fig. 3 is a fragmentary view of the ring after it has been subjected to a milling operation at both of the step-cut ends. Fig. 4 is a fragmentary view of the ring after a tongue has been welded to one of the step-cut ends. Fig. 5 is a view in perspective of the tongue ⁸⁰ before it has been welded in place.

Referring to the drawings, the numeral 12 designates the body portion of a ring having

an internal annular flange 13 at one of its ends. The blank ring can be produced in any suitable manner from tubing. In carrying out my process, the blank ring shown in Fig. 1 is first provided with stepcuts 14 and 16 as shown in Fig. 2 with the step cut 14 extending through the body portion 12 of the ring and into the flanged portion 13 ⁵⁵ and with the stepcut 16 extending through the remainder of the flanged portion 13. The flanged portion 13 is then internally milled on both sides of the stepcut 14 to provide the cutout portions 18 and 20 as ⁶⁰ shown in Fig. 3 whereby the flanged portion adjacent the stepcut 14 is enlarged to the diameter of the body portion 12. A tongue 22 of the proper size and shape to fill in the cutout portions 18 and 20 is ⁶⁵ welded into one of the cutout portions such as the portion 18 so that the free end of this tongue extends into the other cutout portion such as 20 and is slidably positioned therein as shown in Fig. 4 from which figure it will be apparent that this tongue is ⁷⁰ positioned above and adjacent the stepcut 16.

I claim:

The process of manufacturing one piece packing rings which consists in providing a ⁷⁵ blank ring having an internal annular flange at one of its ends, step-cutting said ring so that one of the step cuts extends through the body portion of the ring and into the flanged portion thereof and the other step ⁸⁰ cut extends through the remainder of the flanged portion, internally milling said flanged portion on both sides of the first mentioned step cut to enlarge this portion to the diameter of the body portion of the ⁸⁵ ring, providing a tongue adapted to fill in said milled out portion and welding said tongue at one end in said milled out portion whereby said tongue will be positioned above and adjacent the second mentioned ⁹⁰ step cut.

In testimony whereof I hereunto affix my signature.

GEORGE W. OLNEY
